[57] CLAIM

The ornamental design for a game board, as shown and described.

DESCRIPTION

FIG. 1 is a perspective view of a game board, showing our new design;

FIG. 2 is an enlarged top plan view thereof, the bottom being plain and unornamented;

FIG. 3 is an enlarged right side elevational view thereof, the other side being a mirror image.

FIG. 1

FIG. 3
